PORTABLE POWER UNIT FOR GARDEN TOOLS

Daniel W. Heiniger, Kankakee, Ill., assignor to Sears,
Roebuck and Co., Chicago, Ill., a corporation of New
York

Filed July 15, 1959, Ser. No. 56,792

Term of patent 7 years

(Cl. D35—2)

Fig. 1

Des. 190,665

PAGE 2

Fig. 2

Fig. 3.

FIG. 1 is a perspective view of a portable power unit for garden tools embodying my new design;

FIG. 2 is a side elevational view thereof;

FIG. 3 is a top plan view;

FIG. 4 is a rear elevational view;

FIG. 5 is a side elevational view showing the side opposite that seen in FIG. 2.

The broken-line representation of a cultivator head is shown for purposes of illustration only.

A portion of the shaft is broken away in FIG. 1 to indicate indefinite length and the shaft is broken off in FIGS. 2, 3 and 4 and the handle is broken away in FIG. 3 for convenience of illustration.

I claim:

The ornamental design for a portable power unit for garden tools, as shown and described.
